UNITED STATES PATENT OFFICE.

HERBERT J. TRAVIS, OF NEW YORK, N. Y.

LOCOMOTIVE-BOILER.

No. 821,904.

Specification of Letters Patent.

Patented May 29, 1906.

Application filed May 12, 1905. Serial No. 260,098.

To all whom it may concern:

Be it known that I, HERBERT J. TRAVIS, a citizen of the United States, and a resident of the borough of Brooklyn, in the city and State of New York, have invented a new and useful Locomotive-Boiler, of which the following is a specification.

My invention relates to locomotive-boilers, the object being to provide a boiler of this type which shall be capable of burning pulverized fuel with great economy and high efficiency.

In the accompanying drawings; Figure 1 is a partial longitudinal vertical section through a boiler embodying my invention. Fig. 2 is a transverse section in the plane of the line A of Fig. 1, and Fig. 3 is a horizontal section in the plane of the line B B of Fig. 1.

The boiler, so far as its external shape and general structure is concerned, may be one of the locomotive-boilers in use, and one of the advantageous features of my invention is that it may be readily applied to boilers at present in use as well as to those which may be specially built to embody it.

The outer shell of the boiler is denoted by 1.

The general wall of the fire-chamber is denoted by 2, and the water-space between the shell 1 and fire-chamber 2 by 3. The water-space is continued down the sides and front of the fire-chamber, and the wall 2 is held in proper relation to the shell 1 by numerous tie-rods or rivets 4. The group of fire-tubes leading from the front of the fire-chamber to the uptake is denoted by 5, and the steam-dome by 6. The rear part of the fire-chamber is separated from the front part throughout a considerable portion of its height by a brick wall 7, which, starting at the bottom 8, extends upwardly and gradually curves over toward the rear end of the boiler, finally terminating at a point spaced from the top of the fire-chamber a distance sufficient to permit the products of combustion to pass over it into the front part of the chamber. The brick wall 7 is supported by a series of transverse water-tubes 9, which are secured at their opposite ends in the wall of the fire-chamber, as clearly shown in Fig. 3, and form an open passage for the circulation of water between the water-spaces at the opposite sides of the fire-chamber. These transverse water-tubes

9 are embedded in the brick wall 7 and are conveniently spaced apart the depth of a brick, so that in setting up the wall and transverse wall-supporting tubes a lower brick or line of bricks may be laid in position and a transverse pipe 9 may then be placed in its position, the upper faces or edges of the brick being cut away to form half-round recesses 10 for the reception of the tube, and then another layer of bricks may be laid, having their lower faces provided with half-round recesses 17 for the reception of the upper part of the tube already laid and with half-round recesses in their upper faces or edges for the reception of a succeeding transverse pipe, which may then be placed in position. In this manner the wall 7 may be built step by step and curved over toward the rear of the fire-chamber at such a curve as may be desired, and the said wall will be held securely in position against the blast of the ignited pulverized fuel, and the transverse pipes themselves, which are both supporting-pipes and water-circulating pipes, will be so thoroughly protected from the blast of the ignited fuel that they will not be liable to buckle or deteriorate under its influence.

The pulverized fuel is admitted through one or more pipes 11 at the lower part of the rear wall of the fire-chamber and passes into the chamber under a brick arch 12, where it is ignited, and thence the flame passes forwardly against the rear or concave face of the wall 7, and the mingled flame and gases pass thence upwardly inclined to the rear, and thence over the top of the wall 7 into the forward part of the fire-chamber, and thence through the fire-tube 5 to the uptake.

Doors for gaining access to the interior of the fire-chamber 1, one (denoted by 13) in the side wall of the front part of the fire-chamber and another (denoted by 14) in the side wall of the rear part of the fire-chamber.

Access to the interior of the fire-chamber may also be had through a door 15 in the rear wall of the chamber.

What I claim is—

The combination with the fire-chamber of a locomotive provided with an opening through its rear wall for the admission of a blast of pulverized fuel, of a wall extending upwardly and rearwardly from the bottom of the chamber intermediate of the ends of the

chamber and opposite the inflow of the pul-
verized fuel, the said wall consisting of super-
posed bricks and transverse water-circulat-
ing tubes engaged with the opposite walls of
5 the fire-chamber and housed within and form-
ing a support for the superposed bricks.

In testimony that I claim the foregoing as

my invention I have signed my name, in pres-
ence of two witnesses, this 10th day of May,
1905.

HERBERT J. TRAVIS.
